UNITED STATES PATENT OFFICE.

GLENN R. AMES, OF KANSAS CITY, MISSOURI, ASSIGNOR TO WHITE EAGLE OIL AND
REFINING COMPANY, OF KANSAS CITY, MISSOURI.

DESIGN FOR A GLOBE FOR GASOLINE PUMPS.

Application filed April 17, 1925. Serial No. 13,152. Term of patent 14 years.

To all whom it may concern:

Be it known that I, GLENN R. AMES, a citizen of the United States, residing in Kansas City, in the county of Jackson and State of Missouri, have invented a new, original, and ornamental Design for Globes for Gasoline Pumps, of which the following is a specification, reference being had to the accompanying drawing, forming a part thereof.

The drawing is a perspective view of a globe for gasoline pumps showing my new design.

I claim—

The ornamental design for a globe for gasoline pumps substantially as shown.

In testimony whereof, I have hereunto subscribed my name.

GLENN R. AMES.
